UNITED STATES PATENT OFFICE.

WILLIAM F. MILLIGAN, OF RIDGEVILLE, INDIANA.

FENCE-POST.

SPECIFICATION forming part of Letters Patent No. 609,829, dated August 30, 1898.

Application filed December 7, 1895. Serial No. 571,400. (No model.)

To all whom it may concern:

Be it known that I, WILLIAM F. MILLIGAN, a citizen of the United States, residing at Ridgeville, in the county of Randolph and 5 State of Indiana, have invented a new and useful Fence-Post, of which the following is a specification.

This invention relates to a new and useful improvement in fence-posts; and it consists 10 in the construction and arrangement of parts hereinafter described, and definitely pointed out in the claims.

The aim and purpose of this invention are to construct a fence-post of a single piece of 15 metal which can be easily screwed into the ground and held in an upright steady position by means of a stay-plate surrounding the post, and which is provided with simple means for holding the line-wires. A further 20 object is to construct a fence-post which can be readily placed in position and one which is simple in structure and cheaply manufactured. These and other objects not hereinbefore specified are accomplished by the construction 25 illustrated in the accompanying drawings, wherein like letters of reference indicate corresponding parts in the several views, and in which—

Figure 1 is a perspective view of my improved fence-post, showing portions of the line-wires attached thereto. Fig. 2 is a vertical section of Fig. 1, the base being broken off; and Fig. 3 is a side elevation of a fence with my improved posts applied thereto.

30 In the drawings, A designates my improved post, which is formed of a single piece of metal. The upper portion of the post, which is above the ground, is bent into the form of an oval in cross-section, and the edges a are 35 parallel and firmly crimped or pressed together.

The edges a are provided with a series of 40 slots, in which are adapted to be placed the line-wires E, as plainly shown in the drawings. These slots extend beyond the edges a 45 into the hollow portion of the post, and the line-wires E are held in position by means of the key-rod F, which is adapted to be placed in the hollow portion of the post between the 50 wires and edges a.

The lower portion B of the post is contracted

and is annular in cross-section and tapers down to a point. This lower portion is provided with a screw-thread D, so that the post can be screwed into the ground, thereby dispensing with the necessity of digging a post-hole or driving the post into the ground by force. 55

The post is held in a steady upright position by means of the stay-plate C, which is 60 loosely secured on the post and has a free movement on the post between the screw D and the upper enlarged portion of the post. The post is first started into the ground a short distance, when the stay-plate is forced 65 into the ground and then the post screwed in a sufficient distance. When the post is in its proper position, the plate is in contact with the post and will firmly hold the post in place, and no braces will be needed. The 70 post is screwed into the ground until the upper portion A of the post bears against the plate, thereby helping to hold the plate firmly in position in the ground.

G designates an ordinary stay-wire for the 75 fence-wires.

By making the post oval shape in cross-section it can readily be grasped with a wrench when the post is being screwed into the ground, and the key-rod F is entirely within 80 the post and is protected from the weather and adds to the appearance of the fence. It will further be noticed that the stay-plate C is arranged vertically on the post and that it can readily be forced into the ground when 85 the post is being placed in position.

Having thus described my invention, what I claim as new, and desire to secure by Letters Patent, is—

1. A fence-post formed of a single piece of 90 metal having its lower portion annular in cross-section and tapering to a point, a screw-thread located adjacent to the lower portion of the post, and a vertically-arranged stay-plate loosely and slidably secured on the 95 lower portion of the post and adapted to be forced into the ground when the post is being placed in position to brace the post.

2. A fence-post formed of a single piece of metal having its upper portion formed oval-shaped in cross-section the edges being formed 100 parallel and pressed together, the edges be-

ing provided with slots adapted to receive the line-wires, and the lower portion of the post being formed annular in cross-section and tapering to a point, a screw-thread located adjacent to the lower portion of the post, and a stay-plate loosely and slidingly secured on the lower portion of the post.

In testimony that I claim the foregoing as my own I have hereto affixed my signature in presence of two witnesses.

WILLIAM F. MILLIGAN.
